Specification for Design.

Patented Nov. 16, 1920.

Application filed September 20, 1919. Serial No. 325,257. Term of patent 14 years.

To all whom it may concern:

Be it known that I, GEORGE T. DOCHTERMANN, a citizen of the United States, residing at Passaic, in the county of Passaic and State of New Jersey, have invented a new, original, and ornamental Design for Spark-Plugs, of which the following is a specification, reference being had to the accompanying drawing, forming part thereof.

The figure is a side elevational view of a spark plug, showing my new design.

I claim:

The ornamental design for a spark plug, as shown.

In witness whereof, I hereby affix my signature this 18 day of September, 1919.

GEORGE T. DOCHTERMANN.
